CLAIM

The ornamental design for a connecting plug for cables, as shown and described.

DESCRIPTION

Connecting plug for cables

1.1 : Perspective

1.2 : Top

1.3 : Front

1.4 : Bottom

1.5 : Left

1.6 : Right

In the reproductions, the broken lines are for the purpose of illustrating portions of the connecting plug for cables that form no part of the claimed design.

The back side view is omitted because it is a mirror image of the front side.
